UNITED STATES PATENT OFFICE.

FRED SMITH, OF MOUNT VERNON, INDIANA.

PRINTING BOX.

Application filed April 27, 1920. Serial No. 376,983.

To all whom it may concern:

Be it known that I, FRED SMITH, a citizen of the United States, residing at Mount Vernon, in the county of Posey and State of Indiana, have invented certain new and useful Improvements in a Printing Box, of which the following is a specification.

This invention relates to a printing box and has for its principal object to produce a box into which may be inserted an electric bulb for printing photographs from films or plates.

Another object of the invention resides in the production of means for holding or supporting a plurality of printing frames so that they will be exposed to the light.

With these and other objects in view this invention consists of certain novel arrangements, combinations, and construction of parts as will be hereinafter more fully described and claimed.

In the accompanying drawings:—

Figure 1 is a perspective view of the invention,

Figure 2 is a vertical section taken through a portion of one of the side walls of the device, and

Figure 3 is a central horizontal cross section thereof.

In general the printing box consists of the four side walls as shown thus leaving the box open at its top and bottom, each of these side walls has mounted thereon a support which will also act as a closure for the

openings provided in the walls when the device is not in use or when it is desired to only use a certain number of these openings.

By referring to the drawings by numerals it will be seen that 1 designates the side walls which are held together in any suitable manner so as to provide a top and bottom opening. Each of these walls 1 is provided with the rectangular shaped opening 2

as shown but I reserve the right to make these openings of any desired shape or size.

In order to support a frame in alignment with the openings 2 I have provided the supports 3 which are of the same shape as

the openings and could also be of the same

size. These supports 3 are held adjacent the lower edge of the openings 2 by means of the rings 4 which will also allow the support 3 to be swung upwardly thus closing the opening 2 when same is not in use. In order to firmly support the support 3 in a position at right angles to the walls 1 I have provided the flexible strip 5 which may be of any suitable material. These strips 5 have one end fixedly attached to the wall 1 while the other ends are attached to the outer or bottom face of the support 3.

By referring especially to Figure 2 of the drawings it will be seen that I have provided a latch indicated generally at 6 which consists of a stem mounted upon the knob 9. Spaced apart upon this stem there is situated the two plates 7 and 8 which are spaced from each other a distance equal to the thickness of the walls 1 thus firmly preventing the movement of the support 3 when same is in a closed position.

From the above description it will be seen that I have produced a very simple device which may be cheaply constructed and will be sufficiently durable for its purpose. This device may be constructed of paste-board or any like material. Although I have described the preferred construction of my device I wish it understood that I may make such changes in arrangements of parts, combinations thereof, and constructions thereof that may fall within the scope of the appended claim.

Having thus described my invention what I claim as new is:—

As a new article of manufacture, a printing frame supporting device consisting of a plurality of walls provided with openings, supports hingedly carried by the lower edges of the openings, strips for holding said supports at right angles to the walls, and means for holding the supports in a closed position.

In testimony whereof I affix my signature in presence of two witnesses.

FRED SMITH.
